MICROPHONE AND SUPPORT THEREFOR

Walter D. Olson, Oakland, Calif.

Application January 31, 1949, Serial No. 583

Term of patent 14 years

(Cl. D26—14)

To all whom it may concern:

Be it known that I, Walter D. Olson, a citizen of the United States, residing in the city of Oakland, county of Alameda, State of California, have invented a new, original, and ornamental Design for a Microphone and Support Therefor, of which the following is a specification, reference being had to the accompanying drawing, forming part thereof.

Figure 1 is a front view of a microphone and support therefor showing my new design;

Figure 2 is a side elevational view;

Figure 3 is a top plan view thereof; and

Figure 4 is a front perspective view of the microphone, per se.

I claim:

The ornamental design for a microphone and support therefor, as shown.

WALTER D. OLSON.
